PRESSURE OR LOAD CONTROL DEVICE FOR
METALWORKING PRESSESEinar K. Johansen, Oak Park, Ill., assignor to
Clearing Machine Corporation, Chicago, Ill., a
corporation of Illinois

Application June 12, 1950, Serial No. 167,501

6 Claims. (Cl. 113—38)

1

This invention relates in general to metal working and forming presses of the mechanical type and is particularly directed to a novel form of pressure or load control device which prevents an overload from occurring on certain parts of the press and which may also be used for adjusting and regulating the pressure exerted between certain parts of the press.

The pressure or load control device embodying the present invention is applicable to metal working presses which are mechanically operated and may be applied to different parts of the press to accomplish various specific results, all of which will be clearly set forth hereinafter.

Many metal working presses are so constructed as to consist of a pair of uprights having a crown at one end thereof and a bed at the other end thereof held together by a plurality of tie rods. One form of a pressure or load control device embodying the present invention has heretofore been applied to the tie rods in such a press, and this feature has been disclosed and claimed in my earlier filed copending application bearing Serial No. 154,699, filed April 7, 1950.

Metal working and forming presses, however, differ as to their specific details of construction. Some such presses may have a solid frame without any tie rods to hold the crown and bed together. There are also single action presses wherein an upper slide having a die affixed thereto is caused to come against a metal work piece between the upper die and the lower die located on the bed of the press. Another form of metal working press is known as the double action type wherein a blank holder is first caused to move in a direction to hold the metal blank in place while a second slide, having a die affixed thereto, moves to perform a forming operation. Larger presses may have what is known as a triple action which may be similar to the double action with the addition of a third action slide moving against the blank to cause a further forming operation on the metal blank or work piece. Some of these presses may be operated by driving mechanism located at the top of the press, and others may have the driving mechanism in the lower portion of the press. When the driving mechanism is located in the bottom of the press the frame is not necessarily held together by tie rods, nor is it necessarily a solid frame type.

2

One difficulty which has always been present in metal working presses of the mechanical type is the possibility of stalling or breaking certain parts of the press due to an overload. The overload may be caused by the die setter during the preliminary steps of die setting, if he should set the die in the movable slide too near the opposite die. On the other hand, an operator of the press may occasionally move two blanks instead of one into position on the die which would also cause an overload in the press and either cause some part of the press to break, or may cause the clutch to slip resulting in the press stalling at the end of its normal stroke. It is evident that when press breakage occurs, not only costly repairs are incurred, but also a lengthy delay in production may result during the necessary time for repair.

The pressure or load control device of the present invention is adaptable to presses of the tie rod construction, the solid frame construction, and the type of press wherein the drive is located in the lower portion of the press. The present form of the invention illustrates the applicability thereof to either the blank holder slide or to the slide or slides carrying the forming dies, whether the press be of a solid frame or tie rod construction, or whether it be a single action, double action, or triple action press, and regardless of where the driving mechanism is located.

In most instances the various slides of a metal working press have adjusting means associated therewith in order to adjust the blank holder slide or the draw slides either toward or away from the opposite die to compensate for different pressures, as well as different thicknesses of blanks on which work is to be performed, and varying die heights. In some cases these adjusting means may be adjusted manually, and in larger presses these adjusting means may be operated mechanically.

Heretofore, the variation in thickness of a blank on which the forming operation is to be performed has been a serious problem, because if the blank holder slide or forming slide has been finely adjusted for a particular thickness of stock or blank and then a blank of greater thickness is placed in the press, an overload will occur. The device of the present invention compensates for this variation in thickness of the blank, thus eliminating the necessity for a fine selection in stock

thickness or adjusting the press for each variation. This, in turn, results in great economy because of the reduction in the number of worked pieces or products which must be discarded.

With the foregoing considerations in mind, it is a principal object of the present invention to provide a pressure or load control device which is directly associated with one or more slides in a metal working press.

Another object of the invention is to provide a pressure or load control device which is associated with one or more slides in a metal working press and which compensates for the inaccuracies of a die setter during the preliminary steps of die setting, as well as for the variations in blank thicknesses to prevent an overload in the press from stalling the press or causing breakage to occur therein.

A further object of the invention is to provide a novel form of pressure or load control device in association with the blank holder slide of a metal working press, whereby the pressure exerted by the blank holder slide on the metal blank may be finely adjusted without the necessity for the painstaking adjustment of the adjusting screws.

A still further object of the invention is to provide a pressure or load control device associated with one of the forming slides in a metal working press to protect the press against overload.

Still another object of the invention is to provide a novel pressure or load control device associated with one or more slides of a metal working press wherein a yieldable force will be caused to yield when the pressure created by the slide against the work reaches a predetermined amount, whereby the pressure against the blank may be regulated if the device is associated with the blank holder slide, or the press will be protected against overload if the device is associated with either the blank holder slide or the forming slide or slides of the press.

A further object of the invention is to provide a pressure or load control device for a metal working press, wherein a lever arm is connected at one end thereof between a slide of the press and the mechanism which reciprocates the slide, and the other end thereof is connected to a yieldable means mounted either directly on the slide or on a support member which reciprocates with the slide. An eccentric arrangement adjacent one end of the lever arm will cause the yieldable means to operate when a predetermined pressure or load is reached on the slide with which the device is associated.

Still another and more specific object of the invention is to provide a pressure or load control device for a metal working press wherein a yieldable force such as air or other fluid is exerted against one end of an eccentrically mounted lever arm, thereby to rotate the lever arm in one direction when the fluid cylinder to which it is attached is charged thereby setting up an initial stress. The other end of the lever arm is then connected between one of the slides and the mechanism which reciprocates that slide so that when a predetermined pressure or load is reached, such load will rotate the lever arm in the opposite direction to that in which it was rotated during the charging of the cylinder, thereby to prevent the occurrence of any excessive pressure or overload.

Other objects and advantages of the invention will become apparent upon reading the following

description taken in conjunction with the accompanying drawings in which:

Fig. 1 is an elevational view of the pressure or load control device of the present invention illustrated as applied to one of the forming slides of a metal working press;

Fig. 2 is a vertical sectional view of the device taken along the plane of line 2—2 of Fig. 1;

Fig. 3 is a horizontal sectional view taken along the plane of line 3—3 of Fig. 2;

Fig. 4 is a view partly in elevation and partly in vertical section of two of the devices embodying the invention as applied to the blank holder slide of a press wherein the adjusting screws for the blank holder are manually operated;

Fig. 5 is a horizontal sectional view taken along the plane of line 5—5 of Fig. 6 and illustrating the use of the present invention as applied to a blank holder slide which is adapted to be mechanically adjusted; and

Fig. 6 is a view partly in elevation and partly in section of a press with the invention applied thereto as illustrated in Fig. 5.

In the case of double and triple action presses, the first action slide is sometimes referred to as a blank holder slide which, during the initial cycle of the press, is the first to move against the work or blank to hold it in position while the metal blank is being operated upon by the forming slide or slides.

In a double action press the second action slide is the forming slide which has a die affixed thereto. This forming slide is sometimes mounted within the blank holder slide and is caused to reciprocate vertically. It may also be mounted so as to reciprocate in a direction opposite to that of the blank holder. It is called a second action slide because of the fact that it is operated to cause a forming operation on the blank after the blank holder has come against the blank and during the dwell of the blank holder while it is holding the blank in position. This second slide or forming slide performs its forming operation and then returns to its initial position after which the blank holder returns to its initial position and the product is removed from the press.

Figs. 1, 2 and 3 of the drawings, to which more particular reference will now be made, illustrates the pressure or load control device of the present invention as applied to the forming slide of either a single, double or triple action press. Inasmuch as presses of this general construction are well-known, the details thereof have not been shown, it being sufficient to indicate the slide itself by the numeral 1 which is caused to reciprocate in guideways 2.

The slide is caused to reciprocate by any suitable driving arrangement. In some instances, the slide is reciprocated by a simple crank device. The slides in later improved forms of metal working presses are caused to reciprocate by various linkage and eccentric arrangements for improved operation. The specific driving means, however, is of little importance from the standpoint of the present invention and for purposes of illustration, the drive means for the forming slide has been shown as an ordinary crank device. A drive shaft 4 has an eccentric or crank portion 5 associated therewith to which a link 6 is secured. Ordinarily, the lower end of link 6 will be connected directly by means of a pivot pin to the forming slide thereby to reciprocate the slide as the shaft 4 with the crank 5 thereon rotates.

In the case of a single action press, there may

be only one such crank and link arrangement for the slide. In larger presses of the single, double and triple action types, it is customary to have a plurality of such eccentrics or cranks so that a connection will be made between the crank and the slide either at each corner of the slide structure, or on opposite sides thereof. As far as the present invention is concerned, it may be applied either to a press having a single driving crank, or one having two or more such cranks. In the drawings, only one of the pressure or load control devices has been shown, but it will be understood that more than one such device may be applied to the same slide, if desired.

The pressure or load device of the present invention consists of a cylinder 7 having a piston 8 adapted to reciprocate therein. The bottom 9 of cylinder 7 has an ear or other suitable connecting member 10 arranged so that it may be pivotally connected to a part 11 of the slide by means of a pivot pin 12.

A piston rod 13 is connected to the piston 8 and extends through the top 14 of the cylinder a suitable distance so that its upper end may be connected by means of a pivot pin 15 to one end of a lever arm generally indicated at 16. The lever arm 16 forms a clevis at its opposite end which is provided with circular side members 17 and 18 and an intermediate portion 19 partially surrounding an arcuate recess 20. Each portion 17 and 18 is circular and has a center of curvature as indicated by the arrow 21 in Fig. 2. Each portion 17 and 18 also has an opening therethrough adapted to receive a pin 22 so that the axis of the pin will be eccentric to the center of curvature of the portions 17 and 18. The axis of the pin 22 is indicated by the arrow 23 in Fig. 2 and it will be evident that the distance between the points 21 and 23 is the eccentricity between the axis of the pin 22 and the axis about which lever arm 16 may rotate. The lower end of link 6 extends downwardly into the opening 20 between the sides 17 and 18 of the lever arm 16 and surrounds the pin 22.

The pin 22 also extends between the spaced sides 24 of a bearing member. The bearing member is suitably attached or fixed to the upper part of an adjusting member 28. This adjusting member may assume any suitable form and in this particular instance as illustrated in Fig. 2 of the drawings, it consists of a downwardly extending screw threaded member 29. In the particular embodiment shown, there may be one such screw adjustment at each of various locations on the slide.

An internally threaded bevel gear 30 engages the threaded member 29 and this bevel gear has a flange 31 at one end adapted to rotate in an annular recess provided in a sleeve 32. It will be evident that as the crank 5 rotates to reciprocate the link 6, the link will carry with it the pin 22, the bearing for the eccentric, the screw 29 and the slide 1 mounted thereon. Since the air cylinder 7 is also mounted on the slide, it will reciprocate therewith.

When an adjustment of the slide is desired either for die setting purposes or for adjusting the slide for different thicknesses of metal to be worked upon, the bevel gear 30 may be rotated to thereby cause the slide to be raised or lowered. It will be evident that the stroke of the slide will not be varied because the crank distance is fixed, but the adjustment will determine the lowermost position of the slide with respect to a lower die.

Fluid under pressure is placed in the cylinder

7 above the piston 8 to lower the piston to a point where stop member 3 on lever arm 16 comes against flange 28, as shown in Fig. 2. The fluid pressure against the piston may be varied and will depend upon the size of the press and the amount of pressure of load to be exerted thereby. In the embodiment shown in Fig. 2, it will be noted that the center of the eccentric about which the lever arm 16 rotates and indicated by the numeral 21 is in direct alignment with the center of the crank 5 and the center of the screw 29. The center or axis of the pin 22 in Fig. 2 is located a short distance to the right of the eccentric center 21, this center being indicated by the numeral 23.

15 It will be evident that during the operation of the press, or during the preliminary die setting operation, if the slide is being adjusted, or has been adjusted so that in the lowermost position of the slide a predetermined load will occur, the press may function continuously without trouble. If, however, in the die setting operation the slide is set too low, or if during operation of the press, two work pieces are moved into the die instead of one, or if the work piece is too thick or is uneven so that it is thicker on one side than on the other, this load or pressure exerted by the slide when it reaches the lowermost position will tend to exceed that pressure for which it was originally set. When this condition exists in a press without the present invention applied thereto, either the press will stall due to the fact that the crank cannot continue its movement to the lowermost position thereof, or the press or die may fail or fracture.

35 With the present invention applied to the press as illustrated in Figs. 1, 2 and 3, when the load exerted by the slide multiplied by the eccentric distance between points 21 and 23 exceeds the total fluid pressure acting on the piston 8 multiplied by the length of lever arm 16 due to continued movement of link 6 by operation of crank 5, the force will be transmitted through the eccentric and downwardly on point 23 causing a rotation of lever arm 16 in a clockwise direction, as viewed in Fig. 2. This movement of lever arm 16 will elevate the piston rod 13 and piston 8 against the fluid pressure in cylinder 7, thereby yielding and allowing the crank and link to complete its downward movement without overload or excessive pressure, thereby preventing damage to the press or die or stalling thereof.

45 The eccentric in the form of the invention shown in Figs. 1, 2 and 3 is illustrated with the center line of the crank and screw passing through the axis about which the lever arm 16 rotates, and with the center of the pin 22 on the right-hand side thereof, as viewed in Fig. 2. It will be evident that other specific arrangements of the eccentric may also be had without departing from the spirit of the invention. For example, the center line of the crank and screw may, if desired, pass directly through the center of pin 22. In this case, however, the axis 21 about which the lever arm 16 rotates will still be on the left side of the center of the pin as viewed in Fig. 2, so that the downward force exerted will be on the right-hand side of axis 21 and still cause clockwise rotation of lever arm 16 to move piston 8 upwardly against the fluid pressure in the cylinder 7.

65 70 Another possible arrangement of the eccentric would be to place the axis about which the lever arm 16 rocks on the right-hand side of the center of pin 22. In this arrangement the center line of the crank and screw would pass through the center of the pin and the overload or excessive

pressure would then cause the lever arm 16 to rotate in a counterclockwise direction. When the lever arm rotates in a counterclockwise direction, the piston 8 will move downwardly instead of upwardly, so that it will be necessary to have the fluid pressure in the cylinder below the piston 8 instead of above as illustrated in Fig. 2.

Any of these various arrangements will be obvious to those skilled in the art and will not change the fundamental operation of the invention as disclosed herein.

It may be desirable in instances where more than one adjustment screw is used to have a greater pressure on one side or one corner of the slide than on the other side or corner. This varying pressure can be obtained by the adjustment of the fluid pressure in each cylinder. One cylinder may have the pressure therein increased so that a greater pressure on that corner or side of the slide will be obtained. Thus with the aid of this invention, the pressure which would be exerted on any given point of the slide can be varied by varying the fluid pressure within the respective cylinder or cylinders. In actual practice the rough adjustment may be made by the adjusting screw and the finer adjustment may be made by regulating the fluid pressure within the cylinder.

Referring now more particularly to Fig. 4 of the drawings, this illustrates the pressure or load control device as applied to the blank holder of a double or triple action metal working press, wherein the adjustment of the blank holder may be made manually. The blank holder in a press of this character constitutes the outer slide which reciprocates toward and away from the work to hold the blank in position while the forming slide is performing the forming operation thereon. The spacing members 33 are provided with suitable guideways within which the blank holder 34 is adapted to reciprocate. The blank holder is usually operated by a plurality of cranks or eccentric driving mechanisms having associated therewith links 35.

In the form of press illustrated in Fig. 4 there are four such links 35, one at each corner of the blank holder and two of which may be seen in Fig. 4 of the drawings. The lower end of each link 35 is suitably mounted in a bearing support 36 formed integrally with or otherwise suitably secured to an elongated downwardly extending screw member 37. The screw member 37 constitutes the adjusting screw and passes downwardly through a boss 38 on the blank holder. Each such assembly includes an upper collar 39 and a lower collar 40 having internal threads engaging the threads on the adjusting screw 37.

The adjustment of the blank holder in the press illustrated in Fig. 4 is accomplished manually by means of the collars 39 and 40 on each of the adjusting screws 37. When the blank holder is to be raised the upper collar 39 is loosened and the lower collar 40 is turned against the underside of boss 38. The upper collar 39 is then tightened and that corner of the blank holder remains in adjusted position. The same procedure may then be followed with each of the other adjusting screws 37.

When the blank holder is to be lowered the lower collar 40 is unscrewed and the upper collar 39 is turned to move downwardly against the upper side of the boss 38 to maintain the blank holder in adjusted position. It would not depart from the spirit of the invention to reverse the adjusting mechanism by providing an internally

threaded adjusting screw and make adjusting nuts threadedly engaging the screw at opposite ends thereof.

It is desirable to have a pressure or load control device embodying the present invention associated with each adjusting screw 37 on the blank holder although it is not necessary that this arrangement be followed. The preferred structure of the invention as applied to the type of press illustrated in Fig. 4 is to provide a mounting bar 41 secured at each end thereof to the lower end of adjusting screws 37 at one side of the press. A pair of cylinders 42 may then be mounted side by side on this bar 41 through mounting means such as the ears 43 and pins 44.

Each cylinder 42 has a piston 45 adapted to reciprocate therein and has connected thereto a piston rod 46 extending upwardly through the top of cylinder 42. The upper end of each piston rod 46 is pivotally connected by means of a pivot pin 47 to one end of a lever arm 48. This lever arm 48 is similar in all respects to the lever arm 16 as described previously in connection with Figs. 1, 2 and 3. The lever arm 48 is provided with an intermediate arcuate portion 49 partially surrounding a recess and has side openings to receive a pin 50. The openings through the sides are arranged eccentrically to the center or axis of pin 50 so that the axis of rotation of lever arm 48 will be substantially at the point shown by the numeral 51 in Fig. 4. The axis of pin 50 is indicated by the arrow 52 so that the eccentricity will be the distance between the axis 52 and the axis 51.

As before, fluid under pressure will be applied to cylinder 42 above the piston 45 so that a predetermined force against the lever arm 48 will be necessary to move the piston 45 upwardly against the fluid pressure therein. The operation of the invention as applied to a blank holder is similar in all respects to the operation thereof as previously explained when the pressure or load control device is applied to a forming slide. The invention becomes important with respect to the blank holder from the standpoint of pressure to be exerted against the blank while it is being held during the forming operation. The blank holder must be adjusted for different thicknesses of metal the same as the forming slide and if the metal is of uneven thickness, a greater pressure may be exerted on one side of the press than on the other. Likewise, if two blanks instead of one are inadvertently placed in the press, an excessive pressure will result and cause possible damage to the press or die.

Here again, for any given setting of the blank holder the pressure exerted will be the load times the eccentric distance between the axes 51 and 52. The fluid pressure in the cylinder may also be varied for any given pressure on the blank holder, so that when the pressure on the blank holder multiplied by the eccentric distance exceeds the total fluid pressure against the piston 45 multiplied by the lever distance between pivot pin 47 and the eccentric axis 51, such pressure will be exerted on the axis 52 of pin 50 to move it downwardly resulting in an upward or clockwise rotation of lever arm 48 as viewed at the right-hand side of Fig. 4. This movement, of course, causes piston 45 to move upwardly against the fluid pressure in the cylinder. This yielding action prevents excessive pressure of the blank holder from causing any damage to the press or die.

Again the fluid pressure in each cylinder may

be varied so that it will require more pressure to become excessive at one corner or one side of the press than the other. Also, the adjustment of the blank holder need not be as fine as in presses heretofore known because of the fact that excessive pressure or overload is not hazardous due to the transfer of this excessive pressure to the piston moving against fluid pressure.

Figs. 5 and 6 illustrate a similar arrangement of the invention as Fig. 4, in that the pressure or load control device is applied to the blank holder of a double or triple action press. The difference resides wholly in the manner of adjustment of the blank holder, itself, the adjustment of Figs. 5 and 6 being accomplished mechanically, whereas the adjustment of Fig. 4 is accomplished manually. In Figs. 5 and 6 the spacer members are indicated by the numeral 53, and the type of press shown also includes the tie rods 54 which hold the crown and bed of the press against the ends of the spacer members 53.

The blank holder is shown at 55 and is adapted to be reciprocated in guides 56 provided on the inner sides of the spacer members 53.

Links 57 are secured at their upper ends in any well-known manner to cranks, toggle links or an eccentric drive mechanism, whereby the blank holder 55 may be reciprocated. The lower ends of links 57 are mounted in bearing members 58 each of which has an integral portion 59 extending downwardly through the upper part of the blank holder and terminating in an elongated adjusting screw 60.

Similar to Fig. 4, a transverse mounting bar 61 extends between the lower ends of screws 60 on each side of the machine to accommodate the mounting of cylinders 62 thereon. Each cylinder 62 has a piston 63 adapted to reciprocate therein, and a piston rod 64 extending upwardly from piston 63 through the top of the cylinder 62 and secured at its upper end by means of a pivot pin 65 to one end of a lever arm 66. The lever arm construction 66 is like that of lever arm 48 in Fig. 4 and lever arm 16 in Figs. 1, 2 and 3. This lever arm consists of an arcuate portion 67 partially surrounding a recess between the sides thereof, the sides being provided with an opening for the reception of pivot pin 68. The arrangement is such that the center of the eccentric or the axis about which lever arm 66 rotates is indicated by the arrow 69. The center or axis of pin 68 is indicated at 70. As before, when the blank holder reaches its lowermost position and exerts pressure on the blank to be drawn, the pressure will build up to a predetermined amount. If the device of the present invention is not applied thereto, the pressure may become excessive and thus may cause damage or stalling of the press. With the device of the invention herein applied as illustrated in Figs. 5 and 6, when the pressure of the blank holder reaches a predetermined amount, any pressure which tends to be exerted in excess of that amount will cause the center or axis of pin 70 to move downwardly about the axis 69 as a center, thereby imparting a clockwise movement to lever arm 66 as viewed at the right-hand side of Fig. 6. This movement, in turn, raises the piston 63 against the fluid pressure thereabove in cylinder 62.

When an adjustment of the blank holder is desired it is accomplished mechanically by means of an electric motor 71 mounted on one side of the press. The motor shaft is provided with a pinion 72 in mesh with a gear 73 on shaft 74. A pinion 75 is mounted adjacent each end of

shaft 74 on opposite sides of the center of the press in engagement with a gear 76 on shaft 77. Suitable means on shaft 77, such as a worm screw 77a, engages a worm gear on nut 78 threadedly engaged with each of the adjusting screws 60. Rotation of these gears or nuts 78 will cause the blank holder to be either raised or lowered.

The ends of shaft 77 have bevel gears 79 engaging bevel gears 80 on a shaft 81 at opposite sides of the press. The other ends of each shaft 81 has a bevel gear 82 thereon in mesh with a bevel gear 83 on similar shafts 84. Each shaft 84 has suitable gears thereon adapted to rotate internally threaded gear members threadedly engaged with the adjusting screws at the opposite side of the press, so that operation of motor 71 will cause the blank holder 55 to be raised or lowered at all points thereof simultaneously.

Also, in this form of the invention, although the adjustment of the blank holder may be different from that shown in Fig. 4, the pressure to be exerted on any side or corner of the blank holder can be regulated by the fluid pressure within the particular cylinder associated with any particular adjusting screw.

In my above referred to copending application, the device of the present invention has been described as being associated with one or more of the tie rods in a metal working press. The invention has been disclosed herein as being associated with either the forming slide or the blank holder of a metal working press. It may be desirable to apply the invention to the lower or third action forming slide in a triple action press and this may be done in a manner identical with that herein disclosed with respect to the second forming slide.

The blank holder is often referred to as an outer slide, and it is therefore clear that when the invention herein is referred to as being applied to one or more slides of a metal working press, it is intended to mean that the pressure or load control device may be applied to the slide of a single action press; to either or both slides of a double action press, and to any one or to all three of the slides in a triple action press. It is likewise true that where the press is of a tie rod construction, the device of the present invention may be applied thereto as disclosed in my copending application either alone or in conjunction with one or more of the slides as disclosed herein.

The device has been referred to as either a pressure control device or a load control device. The reason for this is that technically when the device is applied to the outer slide or blank holder, its functions are both pressure regulation, and load control because the pressure of the blank holder against the work is being regulated, and, at the same time, overload is being prevented. When the device is applied to a forming slide of a press, then the primary consideration is the protection against overload. The device, however, functions in the same manner structurally whether its end function is to prevent excessive pressure or to prevent overload. Therefore, throughout this description, as well as in the claims appended hereto, the term "load control" is intended to mean either a means to control the overload on a forming slide or means to control the pressure on a blank holder slide.

In all forms of the invention disclosed herein, it is pointed out that one end of the lever arm is mounted in a bearing in the slide structure. This bearing may be either in the slide itself or in the adjusting means for the slide. The term

11

"slide structure" as used in the claims without further limitation is therefore intended to mean either the slide or the adjusting means therefor.

Changes may be made in the form, construction and arrangement of parts from those disclosed herein without in any way departing from the spirit of the invention or sacrificing any of the attendant advantages thereof, provided, however, that such changes fall within the scope of the claims appended hereto.

Having thus described my invention, what I claim as new and desire to secure by Letters Patent of the United States is:

1. In a metal working press of the mechanical type having a reciprocating slide structure and mechanism for reciprocating the slide structure, a pressure or load control device associated with the slide structure, comprising a yieldable member mounted on the slide structure and movable therewith, a lever arm connected at one end thereof to said yieldable member and having its other end mounted in a bearing in the slide structure to rotate about an axis, a pivot pin passing through said other end of the lever arm and a part of the mechanism for reciprocating the slide structure and having its axis parallel with said first axis and offset from said first axis and from the path of movement thereof, the location of said pivot pin being such that the axial projection thereof is contained within the axial projection of said bearing, whereby relative movement between the slide structure and the mechanism for reciprocating the slide structure tending to produce excessive pressure or overload will cause rotation of said lever arm about said first axis against the pressure of said yieldable member.

2. In a metal working press of the mechanical type having a reciprocating slide structure including adjusting means mounted on the slide, and mechanism for reciprocating the slide structure, a pressure or load control device associated with the slide structure, comprising a yieldable member mounted on the slide structure and movable therewith, a lever arm connected at one end thereof to said yieldable member and having its other end mounted in a bearing in the adjusting means to rotate about an axis, a pivot pin passing through said other end of the lever arm and a part of the mechanism for reciprocating the slide structure and having its axis parallel with said first axis and offset from said first axis and from the path of movement thereof, the location of said pivot pin being such that the axial projection thereof is contained within the axial projection of said bearing, whereby relative movement between the adjusting means and the mechanism for reciprocating the slide structure tending to produce excessive pressure or overload will cause rotation of said lever arm about said first axis against the pressure of said yieldable member.

3. In a metal working press of the mechanical type having a reciprocating slide structure and mechanism for reciprocating the slide structure, a pressure or load control device associated with the slide structure, comprising a fluid pressure means mounted on the slide structure and movable therewith, a lever arm connected at one end thereof to said fluid pressure means and having its other end mounted in a bearing in the slide structure to rotate about an axis, a pivot pin passing through said other end of the lever arm and a part of the mechanism for reciprocating the slide structure and having its axis parallel

12

with said first axis and offset from said first axis and from the path of movement thereof, the location of said pivot pin being such that the axial projection thereof is contained within the axial projection of said bearing, whereby relative movement between the slide structure and the mechanism for reciprocating the slide structure tending to produce excessive pressure or overload will cause rotation of said lever arm about said first axis against the pressure of said fluid pressure means.

4. In a metal working press of the mechanical type having a reciprocating slide structure including adjusting means mounted on the slide, and mechanism for reciprocating the slide structure, a pressure or load control device associated with the slide structure, comprising a fluid pressure means mounted on the slide structure and movable therewith, a lever arm connected at one end thereof to said fluid pressure means and having its other end mounted in a bearing in the adjusting means to rotate about an axis, a pivot pin passing through said other end of the lever arm and a part of the mechanism for reciprocating the slide structure and having its axis parallel with said first axis and offset from said first axis and from the path of movement thereof, the location of said pivot pin being such that the axial projection thereof is contained within the axial projection of said bearing, whereby relative movement between the adjusting means and the mechanism for reciprocating the slide structure tending to produce excessive pressure or overload will cause rotation of said lever arm about said first axis against the pressure of said fluid pressure means.

5. In a metal working press of the mechanical type having a reciprocating slide structure and mechanism for reciprocating the slide structure, a pressure or load control device associated with the slide structure, comprising a yieldable member mounted on the slide structure and movable therewith, a lever arm connected at one end thereof to said yieldable member and having its other end mounted in a bearing in the slide structure to rotate about an axis, a pivot pin passing through said other end of the lever arm and a part of the mechanism for reciprocating the slide structure and having its axis parallel with said first axis and so arranged that a plane passing through both of said axes will be substantially perpendicular to the direction of force through said pivot pin and the axial projection of said pivot pin will be contained within the axial projection of said bearing, whereby relative movement between the slide structure and the mechanism for reciprocating the slide structure tending to produce excessive pressure or overload will cause rotation of said lever arm about said first axis against the pressure of said yieldable member.

6. In a metal working press of the mechanical type having a reciprocating slide structure and mechanism for reciprocating the slide structure, a pressure or load control device associated with the slide structure, comprising a fluid pressure means mounted on the slide structure and movable therewith, a lever arm connected at one end thereof to said fluid pressure means and having its other end mounted in a bearing in the slide structure to rotate about an axis, a pivot pin passing through said other end of the lever arm and a part of the mechanism for reciprocating the slide structure and having its axis parallel with said first axis and so arranged that a plane

13

passing through both of said axes will be substantially perpendicular to the direction of force through said pivot pin and the axial projection of said pivot pin will be contained within the axial projection of said bearing, whereby relative movement between the slide structure and the mechanism for reciprocating the slide structure tending to produce excessive pressure or overload will cause rotation of said lever arm about said first axis against the pressure of said fluid pressure means. 10
